UNITED STATES PATENT OFFICE.

HERMAN J. OSTDIEK, OF MINNEAPOLIS, MINNESOTA.

CALIPER-RULE.

1,343,227.

Specification of Letters Patent. Patented June 15, 1920.

Application filed March 29, 1919. Serial No. 286,096.

To all whom it may concern:

Be it known that I, HERMAN J. OSTDIEK, a citizen of the United States, residing at Minneapolis, in the county of Hennepin and 5 State of Minnesota, have invented certain new and useful Improvements in Caliper-Rules; and I do hereby declare the following to be a full, clear, and exact description of the invention, such as will enable 10 others skilled in the art to which it appertains to make and use the same.

My invention has for its object, to provide a combined caliper rule and square of simple construction and small cost, and to such 15 ends generally stated, the invention consists of the novel construction and combinations of parts, hereinafter described and defined in the claims.

The invention is illustrated in the accompanying drawings, wherein like characters 20 indicate like parts throughout the several views. Referring to the drawings:

Figure 1 is a plan view showing the elements of the tool, extended for use as a 25 graduated scale or rule;

Fig. 2 shows the device just to be used as a square;

Fig. 3 shows the device folded;

Fig. 4 is an enlarged section taken on the 30 line 4-4 of Fig. 3;

Fig. 5 is a plan view of the central or main section of the device; and

Fig. 6 is a plan view of the sliding section of the rule.

The device is made up of three elements, 35 to wit, the main body section 7, a pivoted section 8, and a sliding section 9, all of which parts may be made from thin sheet metal. The main or body section 7 is pro-

vided with an extended portion bent to form 40 a rectangular fold 10, to freely slide. At its outer end, the sliding section 9 is formed with a caliper head 11 that projects therefrom at a right angle, so that the diameter 45 or width of an object may be calipered or measured between the edge 11^a of said head and the parallel end surface 7^a of the body section 7.

To prevent the sliding section 9 from being 50 brought out of the guide fold 10, the former is provided with a raised boss 12 that works freely in a channel formed by an outpressed bead 13, in the offset side of the guide fold 10. This bead 13 and the channel 55 therein, terminate short of the ends of the body section 7, but are long enough to

permit the sliding section 9 to be moved to and from the extreme positions shown in Figs. 1 and 3.

The section 8 is pivoted to the main flange 60 of the body section 7 at 14, and is formed with a laterally pressed boss 15 that will engage frictionally and under spring-action, with any one of three indentations—15^a, 15^b and 15^c, formed in the main plate of the 65 body section 7, eccentric to the pivot 14. When pivoted section 8 is turned into its extended position shown in Fig. 1, boss 15 will engage indentation 15^a and hold the same against accidental movement; when 70 said pivoted section 8 is turned into its vertical position shown in Fig. 2, so as to form a square, said boss 15 will engage indentation 15^b; and when pivoted section 8 is turned to its folded position shown in 75 Fig. 3, boss 15 will engage indentation 15^c. Thus the pivoted section, by a little force applied thereto, may be moved from the one position to the other, but will be held against accidental movements in any one of 80 the three above noted positions, it of course being understood, that the rivet which forms the pivot 14, will be sufficiently tight to cause the engagement of the boss with the indentations under a spring-action. All 85 three of the sections—7, 8 and 9, are graduated in lineal dimensions, usually in inches and fractions thereof, but in some instances, the metric system may be used in these graduations; also it will be understood that 90 in practice, these said elements will be graduated in smaller fractions of the lineal dimension, than is shown in the drawings.

In assembling the parts of the tool, it is only necessary to connect the sections 7 and 95 8 by a single rivet 14, and then to slip the boss-equipped end of the sliding section into the folded guide 10, so that its boss 12 enters the channel of bead 13, and then to press the fold 10 down tightly against the 100 same, thereby interlocking the parts with the section 9, free for sliding movements and incapable of accidental separation from the main body section.

The pivoted section or blade 8 is formed 105 with a longitudinal row of small perforations 16, so that by inserting the point of a pencil through one of these perforations, then moving the blade or section 8 on its pivot 14, circles or segments of 110 circles may be marked.

The manner of folding the main body

section 7 to afford the guide for the sliding section 9, makes the tool of small cost, and as all the parts may be stamped to shape from sheet metal, the entire tool may 5 be made at small cost. The tool is, therefore, especially adapted to be made at such low cost that it may be sold, for example, at 10¢ stores, or may be given away for advertising purposes. However, the tool may 10 be made accurately, and as a high grade tool.

What I claim is:—

1. In a tool of the kind described, the combination with a main body section 15 formed from a flat piece of metal and bent to form a rectangular guide, of a sliding section mounted in said folded guide and provided at its extended end with an offset caliper head, coöperating with the adjacent 20 end of the body section, one side of said guide-fold having a longitudinally extended outpressed bead, and the said sliding section having a boss working in said bead, but coöperating therewith to hold said sliding section against accidental separation 25 from said body section.

2. In a tool of the kind described, the combination with a main body section

formed from a flat piece of metal and bent to form a rectangular guide, of a sliding section 30 mounted in said folded guide and provided at its extended end with an offset caliper head coöperating with the adjacent end of the body section, and a third section pivoted to that end of the body section that 35 is opposite to the end thereof that coöperates with the head of said sliding member, the said pivoted section being adapted to be folded directly against the offset guide fold of said body member.

3. In a tool of the kind described, the combination with a main body section, of a sliding section, slideable in said body section and provided as extended in with a caliper head at its outer rim, and a third section 45 pivoted to that end of the body section that is opposite to the end thereof, that close with the head of sliding member section, the said three sections being graduated in the same lineal dimensions.

In testimony whereof I affix my signature in presence of two witnesses:

HERMAN J. OSTDIEK.

Witnesses:

CLARA DEMAREST,
F. D. MERCHANT.
